DESIGN FOR A COMBINATION BOTTLE STOPPER AND EXTRACTOR

John C. Simpson, Portland, Oreg.

Application January 11, 1946, Serial No. 125,469

Term of patent 14 years

(Cl. D58—10)

To all whom it may concern:

Be it known that I, John C. Simpson, a citizen of the United States, residing at Portland, in the county of Multnomah and State of Oregon, have invented a new, original, and ornamental Design for Combination Bottle Stoppers and Extractors, of which the following is a specification, reference being had to the accompanying drawing, forming part thereof.

Figure 1 is a perspective view of a combination bottle stopper and extractor showing my new design.

Figure 2 is a side elevational view thereof.

I claim:

The ornamental design for a combination bottle stopper and extractor, as shown.

JOHN C. SIMPSON.
